UNITED STATES PATENT OFFICE.

CORA G. DAVISON, OF DENVER, COLORADO.

COLLAPSIBLE BONNET.

1,096,415.

Specification of Letters Patent. Patented May 12, 1914.

Application filed March 21, 1913. Serial No. 756,012.

To all whom it may concern:

Be it known that I, CORA G. DAVISON, a citizen of the United States, residing at Denver, in the county of Denver and State of Colorado, have invented certain new and useful Improvements in Collapsible Bonnets, of which the following is a specification.

The invention relates to a lady's head covering primarily constructed to afford partial collapse thereof when not in use, and capable without change of being used in distinctive styles of head covering.

The main object of the invention is the provision of a head covering which is capable of being extended from normal collapsed condition for use as a bonnet like head covering, or for use in such collapsed condition in the turban style of head covering.

A further object of the invention is the construction and arrangement of parts so that in use of the head covering as a bonnet it may be extended to any degree and thereby partially or wholly cover the head as may be found desirable in the particular conditions under which it is used.

The invention in its preferred form of details will be described in the following specification, reference being had particularly to the accompanying drawings, in which:—

Figure 1 is a perspective view showing the use of the improved head covering as a bonnet in fully extended form. Fig. 2 is a rear view. Fig. 3 is a broken sectional view illustrating the construction. Fig. 4 is a view of one of the forming strips.

In forming the improved head covering I use a section of fabric of the desired texture and color and form therein a series of longitudinally extending parallel tucks or pockets 1, all arranged on one side of the fabric and preferably equally spaced apart. Threaded through these pockets are forming members 2 preferably bowed strips or sections of ratan. From that edge of the fabric forming the rear of the head covering the forming members gradually increase in size, that is the forming member engaging the rearmost pocket is of the smallest size while the next several members gradually increase in size. Throughout the central portion of the fabric strip the forming members are practically of uniform size and then gradually decrease in size toward the front edge of the fabric. The length of the fabric strip materially exceeds the similar dimen-

sion of the forming members, so that when the strip is in place on the members as described the material intermediate the members is formed into a series of irregular folds, simulating Shirring. Fabric intermediate the members is then fixed in this irregular folded condition by a line of stitching 3, which stitching extends throughout the length of the strip intermediate the members except between a few of the different sized members at the rear edge of the fabric.

In arranging the members at the rear edge of the fabric I provide each successive member as much larger than the preceding member as is approximately the width of fabric between the pockets receiving these members. By this construction the rearmost members, of which, while three are shown there may be any number, maintain that section of the fabric included between said members in practically flat condition, forming a partial rear wall for the head covering, the fabric at the lower ends of said members being united to complete said rear wall formation. A panel 4, preferably of similar fabric is then secured to the main fabric within the smallest or rearmost forming member, thus completing the rear wall. Beyond the members so secured together at their lower ends, the remaining members are not united at their lower ends, but the edge of the fabric is hemmed or otherwise finished. The edge of the fabric beyond the forming member at the extreme forward portion is preferably provided with an ornamental strip 5, though this is not essential, and ordinary ribbon strings 6 may be attached to the lower ends of said forward edge, to serve in securing the head covering in place.

By reason of the fact that the lines of stitching are of less length than the adjacent bowed strips, it is obvious that said lines of stitching 3 continually exert a tendency to draw said bowed strips together or toward each other. By this arrangement the head covering when not in use will assume a comparatively flat or collapsed condition, and by virtue of this it is obvious that in the use of the head covering in the style shown in Fig. 1 of the drawings, said covering may be extended to partially cover the head, or to completely cover the head, wholly at the will of the wearer. Hence in this use the improved head covering is adaptable for a great variety of purposes,

as in a form to but partially cover the head it will serve its purpose without interfering with the hair, while in a form to completely cover the head it is an effective protection under all circumstances. In the collapsed condition the head covering may be used to provide a turban style of hat, though in this use the opening within the relatively forward forming member is used to receive the head, while the back of the covering in the bonnet style becomes the top of the turban style.

By reason of the collapsible feature of the head covering it is adapted for many uses of a social nature as but little room is occupied by the covering when not in use, and hence it may be easily and readily stored or held in the lap, as at the theater, without inconvenience.

It is of course to be understood that I contemplate constructing the head covering of any suitable fabric, or of one or more fabrics, and also consider any possible ornamentation as within the spirit of my invention.

What is claimed is:—

1. A head covering including a fabric section having side and rear portions formed to provide spaced pockets, flexible forming members of bowed outline seated in said

pockets, the material intermediate the members in the side portion being provided with a line of stitching of less length than the similar dimension of the adjacent forming members and tending to draw said members into contact, the forming members in the rear portion of the fabric section being of successively increasing size toward the front of the fabric.

2. A head covering including a fabric section having side and rear portions formed to provide spaced pockets, flexible forming members of bowed outline seated in said pockets, the material intermediate the members of the side portion being provided with a line of stitching of less length than the similar dimension of the adjacent forming members and tending to draw said members into contact, the forming members in the rear portion of the fabric being of successively increasing size toward the front of the fabric, and a panel secured within the outline of the rearmost forming member to complete said rear wall.

In testimony whereof, I affix my signature in presence of two witnesses.

CORA G. DAVISON.
